UNITED STATES PATENT OFFICE.

CECIL E. BRIGHAM, OF EAST ORANGE, NEW JERSEY, ASSIGNOR TO C. BRANDES, INC., OF NEW YORK, N. Y., A CORPORATION OF NEW YORK.

ELECTROMAGNETIC SOUND REPRODUCER.

Application filed March 13, 1924. Serial No. 699,107.

To all whom it may concern:

Be it known that I, CECIL E. BRIGHAM, a citizen of the United States, residing at East Orange, in the county of Essex and 5 State of New Jersey, have invented certain new and useful Improvements in Electromagnetic Sound Reproducers, of which the following is a specification.

My invention relates broadly to electromagnetic sound reproducers, and more particularly to an instrument for reproducing 10 radio concerts, music and lectures.

One of the objects of my invention is to provide an extremely simple electromagnetic sound reproducing mechanism which will have the characteristic of accurate sound reproduction where instruments are made in large numbers and where uniformity and permanency of product 15 is of supreme importance.

Another object of my invention is to provide a mounting for the diaphragm in an electromagnetic sound reproducing mechanism in which uniform distance between the magnets and the diaphragm is insured where instruments are manufactured on a quantity production basis, the mounting being so arranged that a cap in which the diaphragm may be centered may 20 be forcibly screwed down upon the electromagnetic casing to lock the diaphragm in permanent operating position, eliminating all necessity of adjusting the instrument after it has initially passed careful 25 factory inspection.

A further object of my invention is to provide a resilient peripheral mounting for the diaphragm in the electromagnetic mechanism on each side thereof, the resilient 30 mounting being such that the resilient characteristic is permanently maintained by reason of the peculiar characteristics of the resilient material which I have discovered for efficient operation of the electromagnetic sound reproducer.

Other and further objects of my invention will be understood from the specification hereinafter following by reference to the accompanying drawings, in which:

50 Figure 1 is a cross-sectional view taken through the electromagnetic sound reproducer of my invention; Fig. 2 is a fragmentary cross-sectional view showing one method which I may employ for mounting the diaphragm in the instrument; and Fig.

3 is a cross-sectional view showing another method which I may employ for mounting the diaphragm in the instrument.

Heretofore in the art ordinary telephone receivers have generally been used in the construction of reproducers in radio receiving apparatus. There has been little change in such telephone receivers since the early days of line wire telephony, and there has been a marked deficiency in radio reproduction due to the lack of analysis of the special problems existing in radio reproduction. I have studied the requirements in electromagnetic sound reproducers, taking into consideration both the alternating current component and the direct current component existing in the output plate circuit of an audio frequency electron tube amplifier, and I have selected an efficient construction of sound reproducer in which a pair of electromagnets is positioned in a casing with an extremely small grinding depth. I provide a cap, screw threaded to engage the casing, with an integral annular ring located within the cap in such manner that in the assembly process a resilient ring, the diaphragm, and a second resilient ring, may be readily centered therein without the exercise of any high degree of skill, and the cap screwed over the casing and firmly anchored thereon. The resilient mounting which I provide for the diaphragm is the result of considerable investigation. A fabric linen ring having a rubberized surface thereon is employed. The ring is extremely thin and the rubber and fabric are each substantially in the nature of a film. The fabric serves to give body to the rubber film and to permanently preserve the same. The rubber, although it is minute in thickness, provides just the amount of resilience which I have found to be necessary in my construction. In assembling the rings and the diaphragm the rubber surfaces of the cloth rings are placed directly adjacent the diaphragm while the cloth surfaces are positioned directly adjacent the periphery of the casing of the electromagnetic sound reproducing mechanism and also directly adjacent the centering ring within the cap of the casing.

Referring more particularly to the drawings, reference character 1 indicates the casing which houses the electromagnetic oper- 110

ating mechanism. A pair of pole pieces 2 and 3 are provided on which are wound the magnet coils 4 and 5 respectively. Permanent magnets 6 and 7 are positioned around 5 the interior of the casing 1 forming magnetic circuits with pole pieces 2 and 3. The permanent magnets are maintained in position by means of kidney members 8 and 9 respectively, being secured to the casing 1 10 by means of screws 8^a and 9^a. The terminals from the magnet windings are brought out to binding posts 10 and 11. The periphery 12 of casing 1 is ground in a plane extremely close to the plane of the pole tips 15 of the pole pieces 2 and 3. A screw cap 14 is provided having an annular depending skirt 15 containing the interior screw threads which engage with exterior screw threads on casing 1. The screw cap 14 is 20 thickened in its central portion as represented by reference character 16 and annular flange 17 provided around screw threaded aperture 18 in the center of cap 14. The screw threaded aperture is provided 25 with an annular counterbored portion 19 immediately adjacent the flange 17 enabling a ferrule 20 to be screw threaded into the aperture 18 and firmly seated with its shoulder 21 against the top surface of flange 30 17. The ferrule 20 serves as a seat and support for the acoustic horn 22.

The cap 14 is provided with an integral depending annular ring 23 on its lower face thereof. A vertical wall portion 24 is provided in the molded cap 14 immediately adjacent its interior surface and spaced from the screw threads on the interior of the cap to provide means for centering the diaphragm mounting within the cap before the 40 casing 1 is engaged therewith.

The resilient mounting comprises a pair of annular rings 25 and 26. Each ring is made up of two dissimilar materials formed integral with each other which I have 45 selected for most efficient operation. Each ring comprises a fabric sheet A and a rubber film B. The fabric sheet and rubber film are substantially molded together or combined in an integral body. Both the 50 fabric and the rubber is extremely thin. The rubber surface of each ring is placed immediately adjacent the diaphragm 27 while the fabric surfaces contact with the periphery 12 of casing 1 and the lower surface of the depending flange 23 of cap 14. The rubber film serves to resiliently support the diaphragm and permit relatively 55 large vertical movement thereof. The rubberized ring 25 is centered in the cap 14 in 60 the construction illustrated in Fig. 2 by matching it with the edge of the depending integral ring 23. The diaphragm 27 is then placed in position upon the rubber surface B of the ring 25 and next the rubberized 65 ring 26 is centered upon the underside of

the diaphragm, being guided at its periphery by the first of the screw threads in the skirt 15, as illustrated in Fig. 2.

In Fig. 3 I have shown a construction which enables the rings 25 and 26 and diaphragm 27 to be readily assembled within the vertical wall space 24 in the cap 14. It will be appreciated that this construction is such as to permit unskilled labor to readily assemble the reproducer. The casing 1 75 may then be screwed into the skirt 15 of cap 14 and firmly tightened in position. No adjustments are required after the initial setting, the particular formation of the rings 25 and 26 affording the required amount of 80 resiliency when the casing 1 is screwed into cap 14 under predetermined pressure.

Again referring to Fig. 1 I provide an annular space 28 beneath the skirt of the cap 14 in which a sealing material may be 85 introduced to prevent tampering with the instrument after it has passed factory inspection. The lower edge of the skirt 15 may be provided with depending tongues 29 to facilitate mounting the instrument in 90 a base.

The present embodiment of my invention has been found to be particularly efficient in operation and practical in construction. The instrument is operated from the output circuit of an electron tube radio receiving apparatus without the employment of an additional energy supply source necessary in many types of electromagnetic sound reproducers and yet its reproduction has good 100 volume and mellow tone quality.

What I claim and desire to secure by Letters Patent of the United States is as follows:

1. An electromagnetic sound reproducer, comprising in combination an electromagnetic operating mechanism, a casing containing said mechanism, a diaphragm, and resilient means for supporting said diaphragm upon said casing comprising a pair of relatively thin rings, one positioned on one side of said diaphragm and the other on the opposite side thereof, each of said rings comprising layers of dissimilar material formed integral with each other, and means 110 for clamping said rings and diaphragm in position.

2. An electromagnetic sound reproducer, comprising in combination an electromagnetic operating mechanism, a casing enclosing said mechanism, a diaphragm, and means supporting said diaphragm on said casing in spaced relation to said electromagnetic operating mechanism comprising a pair of rings, one positioned on one side of said diaphragm and the other positioned on the opposite side thereof, each of said rings comprising a plurality of layers of alternate hard and soft material formed 115 integral with each other, and means for 120 125 130

clamping said rings and diaphragm on said casing.

3. An electromagnetic sound reproducer, comprising in combination an electromagnetic operating mechanism, a casing enclosing said mechanism, a diaphragm, means for supporting said diaphragm on said casing relative to said electromagnetic operating mechanism comprising a pair of rings, one located on one side of said diaphragm and the other on the opposite side thereof, each of said rings comprising a layer of rubber and a layer of cloth formed integral with each other with the rubber layers immediately adjacent said diaphragm, and means for clamping said rings and diaphragm upon said casing.
4. An electromagnetic sound reproducer, comprising in combination a casing, an electromagnetic operating mechanism in said casing, a diaphragm, a screw threaded cap engaging said casing at its periphery, said cap having a short vertical wall portion adjacent its inner surface, and a resilient mounting for said diaphragm adapted to be centered within said short vertical wall por-

tion, said mounting consisting of a pair of rings each comprising alternate layers of different material formed integral with each other with one of said rings located on one side of said diaphragm and the other of said rings located on the opposite side of said diaphragm.

5. An electromagnetic sound reproducer, comprising in combination a casing, an electromagnetic operating mechanism in said casing, a diaphragm, a screw threaded cap engaging said casing at its periphery, said cap having a short vertical wall portion adjacent its inner surface, and a resilient mounting for said diaphragm adapted to be centered within said short vertical wall portion, said mounting consisting of a pair of rings each comprising alternate layers of different material molded one into the other to form a substantially integral body having a rubberized surface, with one of said rings located on one side of said diaphragm and the other of said rings located on the opposite side of said diaphragm.

CECIL E. BRIGHAM.
